(Cl. D44—1)

FIG. 1 is a perspective view of a storage bin, showing my design;

FIG. 2 is a side elevational view thereof on an enlarged scale;

FIG. 3 is a bottom plan view;

FIG. 4 is a sectional view taken on the line 4—4 of FIG. 1;

FIG. 5 is a front elevational view; and

The essential features of my design of a storage bin as disclosed reside in the combination of a downward forwardly extending lip configuration at the forward end of the bin, a generally "V" shaped configuration on the side walls of the bin, and the substantially vertically extending ribs on inner portions of the bin side walls.

I claim:
